2 Sheets-Sheet 2

UNITED STATES PATENT OFFICE.

ALBERT E. F. MOONE, OF CHICAGO, ILLINOIS, ASSIGNOR TO THE LEHON COMPANY, OF CHICAGO, ILLINOIS, A CORPORATION OF ILLINOIS.

ROOFING.

Application filed July 10, 1926. Serial No. 121,643.

The invention relates to what is known in the trade as prepared roofing which usually consists of a foundation sheet of fibrous character commonly called felt, which sheet is impregnated with a waterproof composition and, in many instances, has applied to one side a coating of adhesive asphalt in which a layer of grit is embedded.

This material is so flexible that very little force is required to bend it. Consequently, when laid upon a roof in overlapping courses, the weather portions are likely to be lifted by the elements, permitting rain, snow, or the like to enter between the courses and hence through the roof.

A great variety of expedients have been proposed and tried in an effort to secure the overlapping weather portions against being raised. Some have provided an extra length of material and bent the excess to form a tab underneath the lower margin of the weather portion, which tab was nailed to the roof deck. It happens, however, that prepared roofing cannot be bent while in a relatively cold condition without seriously weakening it along the line of the bend. As a result, proposals based upon this expedient have not been very satisfactory because the connection between the weather portion and the tab failed in such a large percentage of instances as to render the fastening unreliable.

A number of metallic fasteners for use in connection with such tabs have also been proposed, and used to some extent, but they do not entirely overcome the defects and they greatly increase the cost of the roof.

The principal object of this invention is to overcome these defects of the prior art, which is accomplished in the preferred embodiment by providing the weather portions of the roofing, whether in shingle strips, separate shingles, or otherwise, with separately formed hinges having one element or leaf firmly attached to the weather portion adjacent to its lower edge, and another element or leaf pivoted to the first, and adapted to be nailed to the deck in a position below the weather portion. This construction not only results in an efficient and durable fastening for the roof, but assists greatly in locating separate shingles or shingle strips during the operation of laying the roof.

Several embodiments of the invention are

illustrated in the accompanying drawings 55 in which—

Fig. 1 is a plan view of a section of a roof formed of a plurality of roofing strips equipped with hinges according to the invention and laid in overlapping relation 60 upon a roofing deck;

Fig. 2 is a sectional view taken on the line 2—2 of Fig. 1;

Fig. 3 is a perspective view of a portion of one of the shingle strips; 65

Fig. 4 is a plan view of one of the hinges and the head of a roofing nail;

Fig. 5 is a perspective view of one of the hinges indicating by solid and dotted lines the manner of fastening the hinge to the 70 roofing;

Fig. 6 is a sectional view through a roof at one of the hinges;

Figs. 7, 8 and 9 are views similar to Fig. 1, illustrating the invention applied to roof- 75 ing of different shapes.

The roof shown in Figs. 1 and 2 includes a suitable deck 10 and a plurality of shingle strips of the form shown in Fig. 3 laid in overlapping courses. Each strip includes a body portion 11 and a plurality of rectangular tabs 12 projecting from one side of the body portion and separated by narrow rectangular slots 13. The tabs 12 are substantially commensurate with the weather portion of the strips and overlap the body portion of each lower course. Adjacent to its lower edge and at about the middle of its width each tab is equipped with a hinge 14.

In the preferred form shown this hinge 90 includes two loops of wire, A and B, Fig. 5. The intermediate portion 15 of the loop B is substantially straight and the arms 16 and 17 join it at right angles. Between their ends these arms are bent, as indicated at 18, and the portions 19 are first inserted through the tabs from the lower side, then bent from the solid line position to the dotted line position in Fig. 5, and embedded in the upper or weather surface of the tabs, as shown in 100 Fig. 6.

The intermediate portion 20 of the loop A is rounded to form an eye to receive the shank of a roofing nail 21 (Fig. 6) and be overlapped by the head 22, as shown in Figs. 105 4 and 6. The arms 23 of the loop A are wound around the bend 15, as shown at 24, to form a hinge connection between the two

loops which thus become the leaves or butts of the hinge.

Such hinges may be readily made and applied to the tabs by automatic machinery.

- 5 In laying such a roof a starting strip 25, (Fig. 2), is first placed on the deck adjacent to the eves 26. The strips of the first course are held bottom side up below the eves while the eyes 20 of the hinges are nailed 10 to the deck close to the eves after which the strips are thrown upwardly and over to normal position.

Each succeeding course is laid upon the course below with the weather side of the 15 strip down and the normally upper edge at the lower side and with the hinges 14 aligned with the upper edges 27 of the slots 13. A single nail is inserted through each 20 loop 20, the body portion of the strip below and into the deck. The shingle strip is then 25 in the position indicated at C in Fig. 2. It is then thrown upwardly and over to normal position with the tabs below and the body of the strip above.

- 25 It will thus be seen that a single nail serves to secure the body portion of a strip in a lower course and through a hinge also secure a tab of the course above. The hinges form convenient markers for locating the 30 strips in the initial position of the laying operation and no particular care is necessary in turning the strips from that position to their final position on the roof. The 35 comb of the roof may be finished with a cap in the usual manner.

The roof shown in Fig. 7 is similar to that shown in Figs. 1 and 2, except that the tabs 28 have three sides 29, 30 and 31, arranged at angles corresponding to adjacent sides of 40 a hexagon, and are spaced apart by complementary slots 32 whereby the roof is given the appearance of being made of hexagonal elements. The hinges 33 are secured to the lower margins of the tabs at about the middle of their width and function much the same as in the form shown in Figs. 1 and 2.

The roof shown in Fig. 8 is similar to the others described, but in this instance the tabs 34 have two inclined sides 35 connected by 50 a short side 36 to which the hinge 37 is secured.

The roof shown in Fig. 9 is made up of individual square shingles 38 laid with one diagonal extending up the roof and the other 55 extending parallel to the eves. The lower corner is cut away, as indicated at 39 and the hinge 40 is secured adjacent to the edge thus formed. In this construction the nail 41, by which the hinge is secured to the deck, holds 60 the lower corner of one shingle and the upper corner of a shingle in the second course below, while the lower inclined edges 42 of each shingle overlaps and holds the upper inclined edges 43 of two adjacent shingles 65 in the next course below.

In laying this type of roof each shingle is first placed upside down in the position indicated at D in Fig. 9, and the nail 41 is inserted, after which it is thrown over to normal position.

These forms will be sufficient to show those skilled in the art how to apply the invention to prepared roofing in its various forms. In all cases the hinge is a convenience in placing the pieces of roofing and serves to firmly hold the weather portions down against the action of the elements. There is no strain put upon the roofing such as occurs in bending a tab, nor is any particular care required in throwing the pieces of roofing from their initial to their final position.

I claim:

1. A roof comprising a deck and a plurality of overlapping courses of flexible roofing material, each course including a lower exposed weather portion overlapping an upper portion of a course below, and a separately formed hinge secured to the weather portion adjacent to the lower edge thereof and to the roof below the weather portion.

2. A roof comprising a deck and a plurality of overlapping courses of flexible roofing material, each course including a lower exposed weather portion overlapping an upper portion of a course below, and a fastener including a member secured to the weather portion adjacent to its lower edge, and a member pivoted to the first member and nailed to the roof beneath the weather portion.

3. A roof comprising a deck and a plurality of overlapping courses of flexible roofing material, each course including a lower exposed weather portion overlapping an upper portion of a course below, and means for fastening the courses including a separate hinge having two leaves, one secured to the weather portion of each course and the other lying beneath the weather portion and nailed to the deck.

4. A roof comprising a deck and a plurality of overlapping courses of flexible roofing material, each course including a lower exposed weather portion overlapping an upper portion of a course below, and means for fastening the courses including a loop of wire nailed to the deck below the weather portion and a second loop of wire pivotally engaged with the first loop and secured to the weather portion adjacent to its lower edge.

5. A roof comprising a deck and a plurality of overlapping courses of flexible roofing material, each course including a lower exposed weather portion overlapping an upper portion of a course below, and means for fastening the courses including a loop of wire having its end portions se-

cured to the margin of the weather portion of each course, and a second loop nailed to the deck below the weather portion and having its end portions wound about the intermediate portion of the first loop.

6. Flexible prepared roofing adapted to be laid upon a deck in overlapping courses, and a separately formed hinge secured adjacent to one edge of the roof and having 10 a pivoted portion adapted to be folded against one side of the roofing.

7. Flexible prepared roofing adapted to be laid upon a deck in overlapping courses, and a separately formed hinge comprising 15 a loop secured to the roofing adjacent to one edge and the second loop having its ends pivoted on the first loop.

8. Flexible prepared roofing adapted to be laid upon a deck in overlapping courses, 20 and a separately formed hinge comprising a loop having its end portions inserted through the roofing from one side and embedded in the roofing on the other side, and a second loop having its end portions wound 25 about the intermediate part of the first loop to form a hinge connection.

9. A roof comprising a deck and a covering of flexible prepared roofing in overlapping strips, each strip including a body

portion and a plurality of spaced tabs projecting from one side to simulate the appearance of separate shingles, and a hinge secured to each tab near the middle and adjacent to its lower edge, and means beneath each tab for securing the hinge to the deck. 30 35

10. Flexible prepared roofing in strip form, each strip including a body portion, and a plurality of spaced tabs projecting from one side to simulate the appearance of separate shingles when a plurality of 40 strips are laid in overlapping courses, and a hinge secured to each tab near the middle and adjacent to its lower edge.

11. A roofing comprising a deck and a covering of flexible prepared roofing in overlapping strips, each strip including a body portion and a plurality of rectangular tabs spaced apart by narrow slits and projecting from one side of the body to simulate the appearance of shingles, and a hinge having 45 one leaf secured to each tab near the middle and adjacent to its lower edge and another leaf secured to the body of the strip below and adjacent to a spacing slit therein. 50 55

In testimony whereof I affix my signature.

ALBERT E. F. MOONE.
